LEVI L. GILBERT, OF MUSKEGON, MICHIGAN, ASSIGNOR TO THE EM-DEE SUPPLY COMPANY, A CORPORATION OF NEVADA

SURGICAL OPERATING CUSHION

Application filed March 2, 1927, Serial No. 171,922. Renewed October 2, 1929.

This invention relates to a surgical operating cushion for use on a bed or table in performing vaginal examinations, operations and for use in obstetrical cases.

5 Heretofore many forms of invalid mattresses, obstetrical tables and the like have been proposed, many for hospital use and a few intended for portable use to be taken to the patient's home, the latter being awkward 10 to handle and inconvenient to use because limited to one position for the patient. It is accordingly an object of this invention to provide an improved pneumatic surgical cushion 15 that can be positioned on the side of an ordinary bed and to provide means for draining fluids therefrom and at the same time prevent fluids from accidental escape from the cushion.

20 The cushion of this invention is made from two similarly shaped rubber sheets vulcanized or otherwise secured together along the side edges and also inwardly of the edges in a plurality of incomplete annuli. The annuli define rings when the cushion is inflated and the inner ring defines a central well, which well extends to one edge of the cushion. The ends of the rings so formed by the annuli terminate each side of the well so as to allow 25 drainage to the cushion edge from the grooves between the rings so formed. The cushion is inflatable by means of a single valve, inflation taking place in the rings and also 30 between the outermost annulus and the edge of the cushion, thereby providing, when inflated, an air cushion with a plurality of supporting surfaces with drainage spaces between the same communicating with the well so that fluid, no matter where it falls on the 35 cushion, will drain to the well and thence to a waste receptacle near the edge of the cushion.

40 The annuli are so arranged as to form rings of varying sizes in order that the cushion may be comfortable in any position which a patient assumes on the table and also for providing a plurality of rings whereby movement of the patient on the cushion may be accomplished without discomfort of any 45 character.

50 The underside of the cushion, when in-

flated, has substantially the same cross-sectional shape as the top except that the well rests substantially flatwise on the cushion support, whatever it may be.

55 The two sheets may, if desired, be of different materials, such, for instance, as rubber and canvas, which are fastened together in the manner described.

60 When the cushion is deflated, the whole may be readily cleaned and sterilized, as there are no folds, creases, corners or other places likely to retain foreign matter.

65 The rings at one end communicate with one another and also with the space between the outermost annulus and the edge of the cushion so as to allow ready inflation and deflation by means of a single valve.

70 When deflated, the cushion is nothing more or less than two flat pieces of rubber in superposed relation. The fastening together of these two sheets being such as to maintain the thickness of the cushion when deflated at a minimum and also to allow ready cleansing and rolling or folding of the cushion in 75 deflated condition.

75 Other and further important objects of this invention will be apparent from the disclosures in the specification and the accompanying drawings.

80 This invention (in a preferred form) is illustrated in the drawings and hereinafter more fully described.

85 On the drawings:

Figure 1 is a plan view of a bed having a cushion embodying the features of this invention applied thereto.

Figure 2 is an enlarged top plan view of the cushion alone.

Figure 3 is a fragmentary front elevation of a cushion showing the drainage apron.

Figure 4 is a section on the line IV-IV of Figure 2.

Figure 5 is a section on the line V-V of Figure 2.

Figure 6 is a section on the line VI-VI of Figure 2.

Figure 7 is a fragmentary enlarged section on the line VII-VII of Figure 2.

As shown on the drawings:

100 An ordinary bed frame 10 and a mattress

11 are indicated in Figure 1, the surgical cushion of this invention is laid thereon, either by itself or tied at its corners to a stretching frame 12 which helps to prevent shifting of the cushion during movements of the patient.

10 The cushion proper comprises a substantially rectangular pneumatic mattress 13 divided by circular inner rings 14 and 15 into three compartments with a connecting air passage 16 to permit inflation of all the compartments through a single valve 17. The inner ring 15 defines the boundary of a central well 18 formed of the material of the cushion, this well extending to one edge of the cushion through each compartment, as indicated at 19, so that each ring is a broken 15 annulus.

20 When the cushion is deflated, it is simply a trapezoidal double sheet without extra material to form the deep well shown, as I have found that it is a peculiar property of the broken annulus or rings to tend to close up at the gap when inflated, thus automatically 25 providing the extra material to form the depending well 18 as shown in Figure 6, and this shrinkage forms overlapping or re-entrant edges 20 above the portion 19 of the well as shown in Figure 5, that tend to hold the desired shape of the well. The original trapezoidal form of the sheets is chosen to produce a rectangular cushion when inflated.

30 An apron 21 of rubberized sheet material like the cushion proper is cemented to the mouth of the well to hang down over the side of the bed, the free corners of the apron being provided with snap fasteners 22 to enable the apron to be formed into a funnel, as shown in Figure 3, to form a continuation 35 of the overlapping or re-entrant edges 20 of the well at the edge of the cushion, the funnel directing fluids into a receptacle 24 positioned below the bed.

40 In using the cushion for an obstetrical case, the cushion is placed on the bed as shown in Figure 1, and the patient positioned thereon in any desired way such as the lithotomy or Sims position, suitable padding being applied beneath the patient either at the side or end 45 of the pneumatic cushion as the case requires. The channels between the rings act as drainage passages opening into the well 18 and 19 and prevent liquid from overflowing onto the bed, thus maintaining sanitary conditions. 50 The rings in the cushion also facilitate rotating the patient thereon from one position to another without displacing the cushion and without discomfort to the patient.

55 It will thus be seen that I have produced a simple and inexpensive cushion that can be readily cleaned and sterilized and collapsed to a relatively small compass for transportation to and from the patient's home. A large pneumatic surface contributing to the comfort of the patient and in the preferred form

a plurality of rings or dams securing complete protection against overflow.

I am aware that many changes may be made, and numerous details of construction may be varied through a wide range without departing from the principles of this invention, and I therefore do not purpose limiting the patent granted hereon, otherwise than necessitated by the prior art.

60 I claim as my invention:

1. An inflatable operating cushion consisting of two sheets, which, when the cushion is deflated lie in contact with each other over their whole area, said cushion having a plurality of broken annuli formed therein to define concentric air chambers of varying diameter and depth, and also defining fluid conducting channels, and a central well into which the channels open when the cushion is inflated, the said concentric air chambers 65 cooperating when inflated to form a seat or support to facilitate the rotating of a person seated thereon from one position to another without displacing the cushion.

2. A pneumatic surgical cushion including 70 a plurality of incomplete circular air chambers defining a central well, said well extending to one edge of the cushion, said cushion being so arranged that when inflated each side will be of similar shape.

3. A pneumatic cushion comprising two sheets of material fastened together along the edges and also fastened together inwardly of the edges in a plurality of variably spaced incomplete annuli, the portions between the fastened part being inflatable and forming a plurality of incomplete concentric rings, the innermost ring and the ends of the other rings defining a central well which extends to a side of the cushion, the sheets being 75 so fastened together that when inflated the inflated portions will extend symmetrically above and below the fastenings.

4. A pneumatic air cushion formed of two superposed sheets secured along the edges and 80 at intervals inwardly of the edges in a plurality of incomplete annuli providing communicating air spaces between the parts secured together, the innermost annulus defining a central well which extends to one edge 85 of the cushion, an air valve communicating with one of the air spaces so formed, the cushion when inflated being of similar shape and arrangement on the top side and the bottom side.

5. A pneumatic air cushion formed of two superposed sheets secured along the edges and 90 at intervals inwardly of the edges in a plurality of incomplete annuli providing communicating air spaces between the parts secured together, the innermost annulus defining a central well which extends to one edge 95 of the cushion, an air valve communicating with one of the air spaces so formed, the cushion when inflated being of similar shape 100

and arrangement on the top side and the bottom side forming drainage canals communicating with the central well.

5 6. An inflatable operating cushion consisting of two sheets which, when the cushion is deflated, lie in contact with each other over the whole area thereof; said cushion having a plurality of broken annuli formed therein to define concentric air chambers and also defining fluid conducting channels; and a central well into which the channels open when the cushion is inflated.

10 7. An inflatable operating cushion consisting of two sheets which, when the cushion is deflated, lie in contact with each other; said cushion having a plurality of broken annuli formed therein to define incomplete air chambers and a central well and also defining fluid conducting channels; said cushion being so 15 arranged that when inflated each side will be of similar shape.

20 In testimony whereof I have hereunto subscribed my name at Portland, Multnomah County, Oregon.
